UNITED STATES PATENT OFFICE.

HENRY B. BEACH, OF MERIDEN, CONNECTICUT, ASSIGNOR TO THE INTERNATIONAL SILVER COMPANY, OF MERIDEN, CONNECTICUT, A CORPORATION OF NEW JERSEY.

DESIGN FOR A BACK FOR HAND-MIRRORS, BRUSHES, AND SIMILAR ARTICLES.

No. 37,558.

Specification for Design.

Patented Sept. 19, 1905.

Application filed July 1, 1905. Serial No. 268,002. Term of patent 7 years.

To all whom it may concern:

Be it known that I, HENRY B. BEACH, a citizen of the United States, and a resident of the city of Meriden, county of New Haven, and State of Connecticut, have invented a new, original, and ornamental Design for the Backs of Hand-Mirrors, Brushes, and Similar Articles, the same being disclosed in the accompanying drawings, in which the figure is a rear elevation of the back.

I claim—

The ornamental design for a back for hand-mirrors, brushes, and similar articles, as shown.

HENRY B. BEACH.
